CLAIM

The ornamental design for a whistle game call apparatus, as shown and described.

DESCRIPTION

FIG. 1 is a perspective view of a whistle game call apparatus according to the present invention;

FIG. 2 is a bottom perspective view, rotated 180° relative to FIG. 1, of the whistle game call apparatus of FIG. 1;

FIG. 3 is a top view of the whistle game call apparatus of FIG. 1;

FIG. 4 is a bottom view of the whistle game call apparatus of FIG. 1;

FIG. 5 is a left side elevation view of the whistle game call apparatus of FIG. 1;

FIG. 6 is a front elevation view of the whistle game call apparatus of FIG. 1; and,

FIG. 7 is a rear elevation view of the whistle game call apparatus of FIG. 1.
